UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed March 4, 1926. Serial No. 92,121.

This invention relates to improvements in mining machines, and more particularly to machines used extensively in coal mining operations for making the initial or sumping 5 cut in the face of the mine wall or along the edge of the vein being mined, preparatory to blasting whereby the portion of the vein so cut is broken down and the coal removed.

10 The machine embodying the present invention represents a type ordinarily termed a cutting and shearing machine, and is characterized by the mounting of the cutting element on a turntable, which in turn is mounted on a wheeled carriage or truck, whereby the machine is transported on tracks laid on the floor of the mine. Moreover, in this 15 type of machine the cutting element is capable of being swung in an arc as the cutting progresses, in addition to being adjustable to cut horizontally or vertically, and elevated to cut at different levels from the mine floor.

20 The chief object of the present invention is, therefore, to provide a machine that is exceedingly flexible, in the sense that it is capable of use under the different mining conditions which may be encountered, it being borne in mind that the method of attacking a coal vein depends largely on the 25 formation of the vein at the particular point where the cutting is to take place.

The machine herein disclosed is somewhat similar to that illustrated and described in 30 my previous application, Serial Number 33,624, filed May 29, 1925, in fact, so far as the general purpose, design and mode of operation are concerned, the present machine is quite similar to its predecessor. The 35 improvements and therefore, the features which characterize the machine in the present disclosure, have to do more especially with the driving or power transmitting mechanisms to the several operative parts of 40 the machine.

In the main, the present machine may be 45 termed a dual motor driven machine, as distinguished from the single motor drive of its predecessor, that is to say, the power required for actuating certain parts of the machine is derived from one motor, and the power for driving other parts, from a separate motor, with independent controls. These parts, or mechanisms thus driven in-

dependently, may be roughly divided as follows: The cutting mechanism and parts intimately associated with the cutting operations of the machine, are driven by one motor, whereas the mechanisms which transport the machine on its tracks and swing the 55 turntable, are driven from the other motor. Several advantages may be ascribed to this arrangement, the chief one being that once the machine has been positioned for a given cutting operation, only the motor which 60 drives the cutting mechanism need be used, although should such operation require the simultaneous bodily movement of the machine or of the turntable the necessary 65 motive power is available through the other 70 motor. A further advantage of the dual motor drive is the elimination of extended lines of transmission, from a single source of power with the attendant complication of 75 clutch mechanisms and speed increasing or decreasing gearing.

In the accompanying drawings:

Figure 1 is a general top plan view of the machine;

Figure 2 is an enlarged top plan view of 80 the machine with parts broken away and other parts in section, to show the driving mechanisms;

Figure 3 is a view of the machine in vertical section, taken on line 3—3 of Figure 2;

Figure 4 is a view of the machine in side elevation with the cutter head and bar omitted;

Figure 5 is a view in transverse vertical section taken on line 5—5 of Figure 2;

Figure 6 is an enlarged top plan view of 90 the cutter head and parts adjacent, with a portion thereof shown in section, taken on line 6—6 of Figure 3;

Figures 7 and 8 are diagrammatic views in 95 side elevation, showing the positions of the cutting element in normal positions but elevated for cutting at different heights above the mine floor;

Figures 9 and 10 are similar views, showing the cutting head reversed so that the cutter chain is uppermost for making cuts at different levels from the mine ceiling;

Figures 11 and 12 are similar views showing the cutting head turned through 90° 100 for making a vertical cut;

Figures 13 and 14 are top plan views of the machine showing other methods of oper-

ating the machine for making lateral cuts.

Referring first to the main parts of the machine embodying the invention, the same comprises a wheeled platform or carriage A, 5 adapted to be moved on tracks and carrying a cutting element projecting from the forward end of the carriage, said cutting element consisting of a cutting head B and a cutter bar C, extending radially from the 10 base of the cutting head and carrying an endless cutter chain D.

The carriage A comprises a platform or base 1 supported upon a four wheeled truck comprising wheels 2, 2, mounted on front 15 and rear axles 3, 3 journaled in axle bearings 4.

Mounted on the platform 1 is a turntable 5, (Figures 1, 3 and 4) consisting of a heavy solid plate of substantially the same contour 20 as the platform, both being cut away at their forward ends in the form of slots 1^a and 5^a, extending inwardly from their forward edges (Figure 3). The turntable is journaled to swing about the center of the 25 platform, through the medium of a large circular bearing plate 6, housed in a circular opening at the center of the platform and provided at its periphery with a radially extending bearing ring 7, bolted to the turntable and forming a shoulder bearing upwardly against the platform.

Journaled at the center of the bearing plate 6, is a vertical stub shaft 8 having a spur gear 9 keyed at its upper end and above 35 the bearing plate 6, and a mitre gear 10 below said plate. The lower end of the stub shaft is journaled in a bearing 11, fixed to the platform 1. The mitre gear 10 meshes with a pair of mitre gears 12, at the inner ends of 40 two fore and aft propeller shafts 13, journaled in sleeve bearings 14, 14 hung from the under side of the platform 1. At the outer ends of the propeller shafts are mitre gears 15, 15 meshing with other mitre gears 45 16, fixed to the wheel axles 3. This gearing constitutes the drive for transporting the machine along the tracks, the power being delivered to the spur gear 9 through other drive mechanism supported on the turntable 50 and hereinafter to be described.

Mounted upon the turntable 5 is an elevating platform 17 on which is supported the cutting mechanism with its driving mechanism and motor. This elevating platform, however, does not extend over the entire surface of the turntable, a considerable portion at the rear and central portion being cut away to accommodate the axle-driving and turntable-revolving mechanism, including 55 its separate motor, and shown in Figure 1 as located at the lower rear half of the turntable and mounted directly thereto. This platform is tiltably mounted on the turntable by means of trunnions 18, 18 at 60 each rear corner of the turntable, so that

the tilting movement of the platform is about the horizontal axis of these trunnions or generally speaking, about the rear end of the machine. It is to be observed, however, that the lower trunnion 18, in Figure 1, 70 while located at the rear corner of the turntable, is formed in part by an arm 18^a extending transversely from the rear corner of the platform 17. Located forwardly of the trunnions and in longitudinal alignment 75 therewith is a pair of upright gear sectors 19, 19 fixed to the turntable. These gear sectors mesh with pinions forming a part of the platform elevating mechanism, herein- 80 after described.

Mounted at the forward end of the platform is the cutter bar assembly and the driving mechanism thereof, and which will now be described.

Considering first the supports for the cutting mechanism, there is formed integral with the platform a forwardly extending cradle 20, inclined slightly in a downwardly direction, and supporting at its outer end and the main forward bearing 21 for the cutting mechanism, presently to be described in detail.

As clearly shown in Figures 1 and 3, the cutting head B is located just beyond the forward bearing 21, and forms an integral 95 part of a long tubular sleeve bearing for the cutter bar drive shaft, extending rearwardly from this head to a point substantially central of the machine. This bearing sleeve is inclined at an angle of about 15° 100 to the horizontal with its forward end about on a level with the turntable. The rear end of this bearing sleeve 22, is journaled in a rear main bearing 23, integral with the platform 17. Within the sleeve 22, is the main 105 drive shaft 24 with its forward end extending into the cutter head 13. Carried on the sleeve 22 are other operating parts hereinafter to be described.

At the rear end of this shaft 24 and just 110 rearwardly of the main bearing 23, is a gear wheel 25 loosely mounted thereon, but adapted to be thrown into and out of driving connection with the main shaft 24 by a single throw clutch 26, keyed to the end of the shaft. It may be stated at this point that the drawings have been simplified by omitting complete details of the clutches, it being understood that they are of the common form 115 consisting of shiftable collars operated by lever-controlled shifting yokes and provided with clutch teeth which engage complementary clutch teeth on the gear or parts connected with the member on which it is loosely mounted.

As clearly shown in Figure 3, the bearing sleeve 22 extends from the rear main bearing 23 through the front main bearing 21 and carries at its forward end a semi-spherical shaped casing 27 forming one sec- 120 125 130

tion of the cutting head B, all of these parts, including the cutter bar, forming a unit which is capable of being rotated bodily in said main bearings 21 and 23, and about the axis of the main drive shaft 24 which projects into the casing section 27 and carries a mitre gear 28 which in turn delivers power to the cutter chain C through gearing in the cutter head.

10 As shown in Figures 1, 2 and 3 the central portion of the cradle 20 is open and forms a slot 20^a extending rearwardly from the main forward bearing 21, and registering with the slots 1^a and 5^a in the turntable and platform below, thus leaving an open space to accommodate the inclined cutting mechanism assembly. Within this opening or slot is a brace 29 (Figure 3) extending from the under side of the forward main bearing 21 rearwardly and parallel with the axis of the cutter drive shaft 24, said brace being journaled on a pin 29^a extending crosswise of the slot 5^a in the turntable 5 and just above the front axle 3. The forward end of 25 the brace 29 is likewise pivotally connected with the bearing 21 through the medium of ears 21^a depending from the bearing 21, and a removable pin extending through said ears.

Surrounding the bearing sleeve 22 and extending rearwardly from the forward main bearing 21 is a rotatable sleeve 30 having square helical threads cut on its outer surface. This sleeve terminates at its rear end a short distance from the rear main bearing 23, and has keyed thereto a beveled gear 31. Between the beveled gear 31 and said rear main bearing 23, is a sleeve or keyed to the cutter drive shaft 22, at 32^a. A thrust bearing 33 is located between the forward end of the collar 32, and the bevel gear wheel 31, mounted on the threaded sleeve 30. Slidably mounted in a longitudinal slot in the collar 32, is an endwise shiftable locking bar 34, slightly longer than the collar and 40 adapted to be actuated by a pinion 35 engaging rack teeth along one edge of the bar, said pinion being rotated by hand by applying a wrench to a square end 35^a of the pinion shaft. (Figure 2). In the main bearing 23, and at two or more points about the hub of the beveled gear 31, are locking notches 23^a and 31^a respectively adapted to receive the ends of the lock bar 34, this arrangement forming a clutch for locking the 45 collar 32 and bearing sleeve against rotation in the rear main bearing 23 when the locking bar is shifted rearwardly to engage the locking notch 23^a as shown in Figure 2. Similarly by shifting the locking bar 34 forwardly with its end engaging one of the notches 31^a in the hub of the beveled gear 31, the collar 32 together with the bearing sleeve 22 are free to turn as a unit in the main bearings 21 and 23. In fact the entire cutting mechanism can be turned about

the axis of the drive shaft 24, by applying power through the beveled gear 21, as will be later explained.

A large travelling nut 36 is carried on the outer threaded sleeve 30, and is adapted to 70 be normally held against bodily rotation, so that as the threaded sleeve rotates in either direction the nut will travel forwardly or rearwardly along the sleeve. The travelling nut is held against rotation about the sleeve 75 by means of the brace 29 which it will be observed from Figure 3 normally engages the lowermost of the several slots 36^a extending lengthwise of the outer surface of the nut. It will be further observed that there 80 are three of such slots 36^a in the outer surface of the nut, so that any one of them may engage the brace 29 depending on the angular position to which the nut is turned about its axis. To disengage the brace 29 from 85 the groove 36^a in the nut, the journal pin at its forward end is removed, thus allowing the brace to be dropped, thus permitting the nut 36 to turn with the sleeve 30 as is necessary when the entire cutting mechanism is 90 turned in the main bearings 21 and 23.

Referring now to the construction of the cutting head B, and cutter bar C (Figures 1 and 3) the head has already been described as substantially spherical in shape and comprising an upper casing section 27 integral with the bearing sleeve 22. The lower half of the casing is formed by a wall section 37, semi-circular in shape, which is movable relative to the relatively fixed upper section 100 and has sliding contact therewith through the medium of suitable sealing rings 38.

Referring now to the internal mechanism of the cutter head (Figures 2 and 6) a vertical bearing sleeve 40 extends upwardly into the head B, and provided near its upper end with laterally projecting trunnions 41, 41, which are journaled in bearings 42 formed in the side of the head, whereby the entire cutter bar is suspended from the head and 105 is capable of being swung about a vertical axis transverse to the axis of rotation of the drive shaft 23.

As clearly shown in Figure 3, the lower movable section 37 is integral with the bearing sleeve 40, and immediately below the same is an annular bearing sleeve or plate 43, having a downwardly facing bearing surface against which bears the rear end frame member 44 of the cutter bar C, the 110 same having an integral spindle 45 extending upwardly into the sleeve 40, and carrying at its upper end a bearing collar 46, turning on the end of said sleeve. Journaled in the spindle 45 is a vertical shaft 47 having a bevelled pinion 48 keyed at its upper end above the bearing collar 46, and which meshes with intermediate bevelled gear wheel 49, journaled on the trunnions 41, 41, and meshing with the bevelled gear wheel 28. Thus the 115 120 125 130

intermediate beveled gear wheel 49 transmits power from the gear wheel 28 to the gear wheel 48.

The vertical shaft 47 extends below the head 44 of the cutter bar C and has keyed to its lower end a sprocket wheel 50 which drives the cutter chain D (Figure 1) which consists of an endless chain, carried by the cutter bar, and travelling in lateral grooves 10 or tracks 51, along the edges of the cutter bar. The chain carries a series of cutting tools 52 at intervals throughout its length, which perform the actual cutting operation as the cutter bar is advanced laterally. The 15 construction and operation of the cutting bar being old in the art, further details are believed to be unnecessary.

It may be stated at this point that the cutter bar, which includes the spindle 45 extending upwardly into the sleeve 40 within the cutting head B, is capable of being swung in an arc about the axis of the shaft 24, and also to be tilted upwardly and downwardly about the horizontal axis of the trunnions 25 41, 41. The mechanism for swinging the cutter bar laterally will be first described.

As shown in Figure 6, the rear end frame member 44 of the cutter bar is extended on one side laterally at right angles to the bar 30 itself, to form the equivalent of a lever arm 53 having a rearwardly facing clevis 54 formed integral therewith. Extending from this extension 53 rearwardly to the traveling nut 36 is a link 55 having swivel connections at its forward end with said clevis 54 and at its rear end with a clevis 56 on the adjacent side of the nut 36. Thus, as the nut moves along the sleeve 30, forwardly or rearwardly, as the sleeve is rotated in either direction, the entire cutter bar is swung in the cutting plane of the chain, the full swing of the bar being from 60° to 90°, or from 30° to 45° on either side of the longitudinal center line of the turntable.

Referring now to the driving mechanism for the cutter bar, the prime mover is an electric motor 57 mounted at the rear end of the platform 17. The armature shaft of the motor extends from the forward end of the 50 motor casing and carries a beveled pinion 58 which drives a primary drive shaft 59 extending oblique and parallel with the end portion of the cutter bar drive shaft assembly, and is journaled in a bearing 60 located 55 below the rear end of the cutter bar drive shaft 24 (Figure 3). This primary drive shaft carries at its rear end a beveled gear 61 meshing with the armature pinion 58 and at its opposite or lower end a spur pinion 62 (Figure 2).

Immediately above and forward of the primary drive shaft 59 is a secondary or intermediate drive shaft 63, journaled in a bearing 64 mounted on the platform 17, and carrying at its rear end a spur gear 65,

meshing with the spur pinion 62 and also with the cutter bar driving gear 25. Thus the drive from the motor to the cutter bar is through the gears 58, 61, 62, 65 and 25 respectively, and controlled by the clutch 26. 70

The secondary shaft 63 is likewise arranged parallel with the axis of the cutter bar drive shaft assembly and carries near its lower end a pair of spur gears 66 and 67 (Figure 2), spaced apart, and both loosely 75 mounted on the shaft. Associated with each of these gears is a clutch 68 and 69, respectively, the same being preferably operated by a unitary clutch lever whereby one is released as the other is thrown in, and vice 80 versa. The uppermost or right hand gear wheel 66 is somewhat larger than the gear wheel 67 at the lower end, there being another gear wheel 70 of the same size meshing with the latter, and positioned just above 85 and a little to one side thereof.

Extending parallel with the secondary shaft 63 is still a third driving shaft 71, likewise arranged oblique to the horizontal and parallel with the shafts 59 and 63. This third or final drive shaft is supported in bearings 72, 72, at each end likewise mounted on the platform 17, and is positioned above and outwardly from the secondary shaft 63 near the edge of the platform. 95

Intermediate the ends of this final drive shaft are two spur gears 73 and 74 fixed to the shaft side by side, the one on the right (Figure 2) meshing with the larger gear wheel 66 on the secondary shaft 63, and the other meshing with the intermediate gear 70 which is driven from the smaller gear wheel 67 on the secondary shaft. This arrangement of gearing, therefore, provides for the driving of the final drive shaft in either 105 direction, i. e., forward or reverse, by the shifting of the clutch members 68 and 69. At the lower end of the final drive shaft is mounted a worm 75 meshing with a worm wheel 76 immediately below, and fixed to the 110 end of a transverse shaft 78 journaled in a bearing 77. This shaft extends toward the cutter bar drive shaft assembly and carries at its inner end, a beveled gear 79 meshing with the beveled gear 31 carried by and turning with the threaded rotative sleeve 30 controlling the lateral swinging movement of the cutter bar through the traveling nut 36 and connecting link 55. It is to be observed however, that when the lock bar 34 is shifted 115 to connect the beveled gear wheel 31 to the collar 34, the entire cutting mechanism can be turned in the main bearings 21 and 23, to secure the desired cutting angle or plane of the cutter bar. 120

At the rear or upper end of the final drive shaft 71 is another worm 80 loosely mounted on the shaft, but capable of being connected therewith through a clutch member 81. This worm meshes with a worm wheel 82 125

(Figure 3) immediately below, the same being fixed to a shaft 83 extending transversely the full width of the platform 17, and having bearing near its ends in bearings 84 and 84, and centrally in the main rear bearings 23 of the cutter bar drive shaft assembly (Figure 3).

At the extremities of said shaft are pinions 85, 85, which mesh with the upright gear sectors 19 which are anchored to the turntable 5. This mechanism just described constitutes the platform elevating and lowering mechanism and is controlled by the clutch 81 which is thrown in when the shaft 71 is being driven in the proper direction to lower or raise the platform as desired.

The foregoing completes the mechanism for driving and controlling the cutter bar in its movement relative to the turntable, and including the elevation of the platform on which said cutting mechanism is mounted. There remains, therefore, the driving mechanism for transporting the machine on its track, and for swinging the turntable in a horizontal plane.

As already suggested, a separate motor and drive gearing is used for this purpose, the motor 86 being located at the rear of the turntable and immediately adjacent to the motor 57 but differing in its mounting in that it is fixed to the turntable 5 whereas the motor 57 is fixed to the platform 17 and moves with it.

The gearing driven by the motor 86 will now be described. A pinion 87 is fixed to the motor armature shaft projecting from its forward end, and meshes with a spur gear 88 fixed at one end of a horizontal drive shaft 89 offset to one side of the armature shaft 40 and journaled in a bearing 90 supported on the turntable, (Figures 2, 4 and 5). Keyed to the shaft 89 intermediate its ends is a drive pinion 91 and at its forward end is a mitre gear 92 meshing with another mitre gear 93 loosely mounted on a vertical stub shaft 94 (Figure 5), extending from the turntable upwardly through a gear casing 95 formed integral with a bearing 96 supported upon the turntable. At the lower end of the shaft 94 is fixed a spur gear 97 lying in the plane of the spur gear 9 fixed to the upper end of the axle drive stub shaft 8 and meshing therewith.

The gear casing 95 is located above the turntable and encloses a worm wheel 98 keyed to a sleeve 99 turning loosely on the shaft 94. Also keyed to the shaft 94 and below the gear casing 95 is a double clutch throw member 100 adapted to be shifted in opposite directions, that is, downwardly to engage the beveled gear wheel 93 or upwardly to mesh with clutch teeth 99^a at the lower end of the sleeve 99, carrying the worm wheel 98. Moreover, the clutch member may

be shifted into an intermediate or neutral position, which permits the bevel gear wheel 93 to idle on the shaft 94.

The gear casing 95 also encloses one end of a worm shaft 101 carrying a worm 102 meshing with the worm wheel 98. This worm shaft 101 extends from the gear casing 95 and carries at its free end a spur gear wheel 103, meshing with the intermediate fixed gear wheel 91 on the drive shaft 89 (Figure 2).

The mechanism and gearing thus far described, has to do entirely with the drive to the axles and wheels for moving the machine along the tracks. Moreover, the mechanism described provides for both low and high speed, in either forward or reverse directions. Thus it will be seen that, in the neutral position of the clutch 100, no power is delivered to the shaft 94, since both the bevel gear 93 and the worm gear 98 are idling on the shaft, although both are always in driving engagement with the shaft 89, the beveled gear 93, being driven through the beveled gear 92, and the worm wheel 102 through the worm shaft 101 and the intermediate spur gear 103 on said worm shaft. Now, by shifting the clutch 100 downwardly the power is transmitted directly from the shaft 89 to the stub shaft 94, through the intermediate train of gears 95 92, 93, 97 and 9, with some reduction in speed. On the other hand, by shifting the clutch upwardly the power is now transmitted through the worm gearing, to the shaft 94 and thence to the axles through the same train of gearing from the lower end of the shaft 94. In following the train through the worm drive, however, there is an additional step in the train which brings about a reversal of direction at the wheels, so that by driving through one train the direction of movement is the reverse of that obtained in driving through the other train.

In somewhat the same manner that power is delivered from the lower end of the vertical shaft 94 for driving the truck wheels, power is delivered from the upper end of the same shaft for revolving the turntable about its central bearing on the main platform of frame 1. This will now be described.

At the upper end of the sleeve 99 is a spur gear 104 (Figures 1, 4 and 5) which meshes with a gear wheel 105, lying in the same horizontal plane, just above the top of the motor 86 and forming the second of a train of gear wheels between the driving shaft 94 and a vertical driven shaft 106 mounted at the extreme edge of the turntable to the rear of the motor 86. This driven shaft is journaled in a bearing 107 integrally connected with the turntable 5 and carries at its upper end a gear wheel 108, this being the last of the four gear wheels of the train,

and meshes with the third gear wheel 109 which in turn meshes with the second gear wheel 105 (Figure 4).

At the lower end of the driven shaft 106 is a pinion 110, which meshes with a curvilinear rack or gear sector 111 (Figures 1, 2 and 4) and consisting of teeth cut in the rear edge of the main frame or plate 1 of the machine. This pinion 110 is loosely mounted on the shaft 106, and is connected thereto by means of a clutch member 112 keyed to the shaft and shiftable into and out of clutching engagement with said pinion.

Thus by shifting the clutch 100 into neutral position and operating the motor 86 in the proper direction, the gear train 104, 105, etc., is driven from the worm wheel 98, to swing the turn table in either direction when the clutch 112 is thrown in to connect the gear wheel 110 with the shaft 107.

As is customary in machines of this character, the control levers are centralized so that the machine operator can control the machine from one position, but since this scheme is not novel in the present machine, the controls are omitted.

This completes the detailed description of the machine and its operating parts, and the remaining descriptive matter will be devoted to a discussion of the operation of the machine with the aid of Figures 7 to 16 of the drawings.

Figure 7 shows the machine in position for making a lateral cut at the level of the mine floor, where it is desired to undercut the vein immediately in front of the machine.

Figure 8 shows the position of the cutter bar in making a lateral cut at a level above the floor, this being accomplished by elevating the platform 17 to an inclined position and at the same time tilting the cutter bar downwardly into a horizontal position, so as to compensate for the normal inclination of the cutter driving mechanism.

Figure 9 shows the position of the machine in making a cut close to the ceilings of the mine. This position shows the cutter head being revolved through an angle of 180° so that the cutter chain is uppermost.

Figure 10 shows the position of the machine in making a cut substantially midway between the floor and the ceiling, the height being such that the platform may be lowered as in Figure 8, but the cutting head and cutter bar are turned upwardly or through 180° from the position shown in Figure 8.

Figures 11 and 12 show the manner in which the machine may be operated in making a shearing cut, that is, a vertical cut from top to bottom in the vein immediately ahead of the machine. Figure 11 shows the machine about to make the initial cut, the cutter head and bar being revolved through 90° so that the bar is brought into

a vertical plane and inclined upwardly at an angle of about 45°. In this position the machine is propelled forward on the track and when the desired depth is reached the machine is brought to rest and the cutter bar swung in a downward direction to the floor level. Figure 12 shows the same vertical cutting operation carried out where the ceiling is considerably higher than that shown in Figure 11. In this case the added vertical reach is obtained by elevating the platform 17, thereby increasing the vertical range of the cutter bar.

Figure 13 shows the machine making a cut in the side wall and parallel to the tracks in which the machine moves. In this position the turntable is swung at an angle of 45° toward the side wall and the cutter bar positioned at 45° to the turntable, so that it stands at right angles to the tracks. Thus, by moving the machine bodily along the track, the cutting progresses in the direction of the movement of the machine.

Figure 14 represents the cutting operation in which the cutter bar is swung from right to left in an arc without moving the machine until the cutter bar has swung through an arc of substantially 90°, whereupon the cut is continued in a straight line by swinging the turntable from right to left until the cut has been completed, either by bringing the cutter bar out of the cut with a swinging cut or by withdrawing the cutter bar before the cut has been completed and then moving the machine bodily to the left and continuing the cut in a lateral direction from right to left.

From the foregoing explanation it will be seen that the machine is exceedingly flexible and is capable of meeting substantially all the conditions which may be met in mining operations. Structurally the machine is exceedingly light and compact considering the rather intricate mechanism required for adjusting the parts into the several cutting positions obtainable and for directing the cutter bar along a prescribed line of cutting.

Although I have shown and described one form in which my invention may be embodied, it will be understood that the construction and arrangement of the different parts may vary widely without departing from the spirit and scope thereof. Furthermore, I do not wish to be understood as limiting myself to the specific construction illustrated herein, excepting as it may be limited in the appended claims.

Therefore, having heretofore described the structure of my machine, its advantages, and the conditions under which it may be operated,

I claim as my invention:

1. In a mining machine, the combination of a wheeled carriage, a turntable mounted on said carriage, an elevating platform tilt-

- ably mounted on said turntable, cutting mechanism mounted on said platform, driving mechanism for said cutting mechanism mounted on said platform, and independent driving mechanism mounted on said turntable for operating the same. 65
2. In a mining machine, the combination of a wheeled carriage, a turntable mounted on said carriage, a tiltable platform mounted on said turntable, cutting mechanism mounted on said platform, driving mechanism for said cutting mechanism mounted on said platform, and independent driving mechanism mounted on said turntable for 70 moving said carriage and turntable. 75
3. In a mining machine, the combination of a turntable, a tiltable elevating platform mounted on said turntable, cutting mechanism mounted on said platform, driving mechanism operatively connected with said cutting mechanism elevating mechanism operatively connected with said platform, a motor mounted on said platform and having driving connections with said driving and 80 elevating mechanisms, and a motor mounted on said turntable and having driving connections therewith. 85
4. In a mining machine, the combination of a turntable, a platform hinged at one end 90 to said turntable, cutting mechanism mounted at the opposite end of said platform, driving mechanism mounted on said platform and comprising a motor in operative connection with said cutting mechanism, means 95 driven by said motor for raising and lowering said platform, and a separate motor and driving mechanism carried by said turntable for swinging the same about its axis. 100
5. In a mining machine, the combination of a wheeled carriage, a turntable mounted on said carriage, a platform hinged to said turntable and adapted to be tilted about the rear end thereof, cutting mechanism carried at the forward end of said platform, a motor 105 mounted adjacent the rear end of said platform, driving mechanism intermediate said motor and said cutting mechanism, elevating mechanism for said platform driven through said driving mechanism and independent 110 driving mechanism including a motor for propelling said carriage and for swinging said turntable. 115
6. In a mining machine, the combination of a wheeled carriage, a turntable pivotally mounted centrally of said carriage, a platform hinged at one end to the rear of said turntable, cutting mechanism supported at the forward end of said platform, a motor mounted adjacent the rear of said platform and having driving connection with 120 said cutting mechanism, elevating mechanism for said platform operative by said motor, an auxiliary motor mounted on said turntable, and means driven by said last men- 125
- tioned motor for actuating said carriage and turntable. 130
7. In a mining machine, the combination of a wheeled carriage, a turntable mounted on said carriage, a platform having hinged connection at the rear of said turntable, a cutter mounted at the forward end of said platform, driving mechanism and elevating mechanism associated with said cutter and platform respectively, a motor operatively connected with said cutter driving and platform elevating mechanisms, clutches interposed between said motor and said cutter driving and platform elevating mechanisms, a separate motor mounted on said turntable, and gearing driven by said last mentioned 135 motor and operative to propel said carriage and to swing said turntable. 140
8. In a mining machine, the combination of a wheeled carriage, a turntable mounted to swing in a horizontal plane about the center of said carriage, a platform having hinged connection with said turntable and adapted to be tilted about the rear end thereof, cutting mechanism carried at the forward end of said platform, a motor mounted adjacent the rear end of said platform, driving mechanism intermediate said motor and said cutting mechanism, auxiliary driving mechanism for elevating said platform operatively connected with said motor, said platform having a portion removed adjacent its rear end, and separate driving mechanism including a motor for propelling said carriage and for swinging said turntable, mounted on said turntable and within the space provided by the removed portion of said platform. 145
9. In a mining machine, the combination of a wheeled carriage, a turntable mounted on said carriage, a platform having hinged connection at the rear of said turntable, a cutter bar mounted at the forward end of said platform, driving mechanism associated with said cutting bar, including a motor mounted on said platform, platform elevating mechanism mounted on said platform and operatively connected with said motor, a separate motor mounted on said turntable, and a gear train driven by said last mentioned motor and operatively to propel said carriage and to swing said turntable. 150
10. In a mining machine, the combination of a wheeled carriage, a turntable mounted on said carriage, an elevating platform tiltably mounted on said turntable, elevating mechanism for said platform, cutting mechanism mounted on said platform, driving mechanism mounted on said platform and operatively connected with said cutting and elevating mechanisms, and independent driving mechanism including a motor for operating said turntable. 155
11. In a mining machine, the combination of a wheeled carriage, a turntable mounted

on said carriage, an elevating platform tiltably mounted on said turntable, cutting mechanism supported on said platform, a motor mounted on said platform and having driving connection with said cutting mechanism, elevating mechanism for said platform operatively connected with said motor, and a sepa-

rate motor for driving the carriage and said turntable.

Signed at Davenport, in the county of ¹⁰ Polk and State of Florida, this 17 day of February, A. D. 1926.

CHARLES E. DAVIS.
